US0D1055083S

(12) **United States Design Patent** (10) **Patent No.:** **US D1,055,083 S**
(45) **Date of Patent:** **** Dec. 24, 2024**

(54) **DISPLAY PANEL OR SCREEN OR PORTION THEREOF WITH GRAPHICAL USER INTERFACE**

(71) Applicant: **SONY GROUP CORPORATION**, Tokyo (JP)

(72) Inventors: **Keiichi Yoshioka**, Tokyo (JP); **Hiroshi Ikeda**, Tokyo (JP); **Naoki Nomura**, Kanagawa (JP); **Takashi Ito**, Tokyo (JP)

(73) Assignee: **SONY GROUP CORPORATION**, Tokyo (JP)

(**) Term: **15 Years**

(21) Appl. No.: **29/817,833**

(22) Filed: **Dec. 3, 2021**

(30) **Foreign Application Priority Data**

(57) **CLAIM**

The ornamental design for a display panel or screen or portion thereof with graphical user interface as shown and described.

DESCRIPTION

FIGURE is a front view of a display panel or screen or portion thereof with a graphical user interface showing our new design.

The outermost broken lines shown in the drawings represent the display panel or screen or portion thereof with a graphical user interface that form no part of the claimed design. The broken lines in the graphical user interface illustrating portions of the graphical user interface form no part of the claimed design.
